UNITED STATES PATENT OFFICE.

RICHARD WYLIE, OF NAPA, CALIFORNIA.

SWEEPER.

No. 806,226.

Specification of Letters Patent.

Patented Dec. 5, 1905.

Application filed January 25, 1905. Serial No. 242,631.

To all whom it may concern:

Be it known that I, RICHARD WYLIE, a citizen of the United States, residing at Napa, in the county of Napa and State of California, 5 have invented certain new and useful Improvements in Sweepers; and I do declare the following to be a full, clear, and exact description of the invention, such as will enable others skilled in the art to which it appertains to make 10 and use the same, reference being had to the accompanying drawings, and to the letters of reference marked thereon, which form a part of this specification.

This invention relates to new and useful 15 improvements in sweepers; and the object of the invention is to produce a simple and efficient apparatus of this nature whereby the rotary sweeper is mounted upon the end of a shaft and rotated by means of a friction-wheel 20 which is made to contact with a driving-wheel positioned at right angles to the broad face of the sweeper, means being provided whereby the driving-wheel and shaft carrying the same may be turned over, rendering the apparatus 25 practicable for sweeping continuously to the same side, although going first one way and then the opposite direction.

The invention consists, further, in various 30 details of construction and in combinations and arrangements of parts, which will be hereinafter fully described and then specifically defined in the appended claims.

My invention is illustrated in the accompanying drawings, in which—

35 Figure 1 is a perspective view of my improved sweeping apparatus. Fig. 2 is a top plan view, and Fig. 3 is a detail view, in central section, of the sweeper.

Reference now being had to the details of 40 the drawings by letter, A designates a handle-bar which may be hollow or solid, as may be desired, and has a cross-piece B fixed in an eye at the outer end of said shaft. Mounted upon said handle-bar is a sleeve D, having an 45 enlarged end D', and E designates an angled axle-shaft, on one end of which is journaled the driving-wheel F, said angled shaft being secured to the sleeve by a bolt H. Swiveled in said enlarged portion D' of the sleeve is 50 the head K of the rotatable shaft K', and L designates a friction-wheel fixed to said shaft K' and is adapted to frictionally engage the face of the wheel F, as shown clearly in Fig. 2 of the drawings, whereby an accelerated 55 motion may be imparted from the wheel L to the driving-wheel. A rotary sweeper Q is

held between the disks Q' upon the shaft K', nuts O being fitted upon the threaded shaft K' and designed to clamp said disks frictionally against the opposite faces of the brush. 60 A thumb-screw N is carried in an aperture in the angled arm of the axle on which the wheel F is mounted, and the inner end of said thumb-screw is designed to bear against the head of the sleeve D for the purpose of regulating the 65 frictional contact between the wheels L and F. By turning the screw N in one direction it will be observed that the wheels will be drawn together, while in the opposite direction they will be thrown away from each 70 other, said screw turning in a threaded aperture in the angled arm of the axle.

By the construction shown in the drawings it will be observed that when it is desired to turn the driving-wheel and shaft so that it 75 will be positioned on the opposite side of the handle-bar the latter is raised slightly, allowing the weight of the apparatus to rest upon the edge of the brush, and by means of the 80 swiveled connections between the shaft K and the sleeve said handle-bar may be readily turned so that the driving-wheel will be positioned in a plane parallel to the position shown in Fig. 2 of the drawings.

By the provision of the apparatus shown it 85 will be observed that a simple and efficient sweeping-machine is provided whereby the rotary brush may be drawn or pulled, and by the throwing of the driving-wheel upon one 90 side or the other of the handle-bar it will be observed that a person may draw or pull the brush back and forth, causing the brush to make a continuous sweeping movement in the same direction.

Having thus fully described my invention, 95 what I claim as new, and desire to secure by Letters Patent, is—

1. A sweeping-machine comprising a handle-bar, a sleeve on said bar, an angled axle secured to said sleeve, a driving-wheel journaled upon said axle, a rotary brush swiveled to said bar, a friction-wheel adapted to contact with said driving-wheel for rotating the brush, and means carried by said axle and cooperating with said sleeve for regulating the frictional contact between the wheels, as set forth. 105

2. A sweeping apparatus comprising a handle-bar, a sleeve on said bar, an angled axle secured to said sleeve, a driving-wheel journaled upon said axle, a swiveled shaft carried by said handle-bar, a brush fixed to said swiveled shaft, a friction-wheel also fixed upon said swiveled 110

shaft and adapted to contact with said driving-wheel, and means carried by said axle and coöperating with said sleeve for regulating the frictional contact between said wheels, as set forth.

- 5 3. A sweeping apparatus comprising a handle-bar, a sleeve mounted upon said bar, a rotary sweeper and shaft to which said sweeper is secured, said sweeper-carrying shaft having a head which is swiveled in said sleeve, a friction-wheel mounted upon the sweeper-carrying shaft, an angled axle mounted upon said sleeve, a driving-wheel journaled upon said

axle and adapted to contact with said friction-wheel, a thumb-screw passing through the angled end of said axle and adapted to bear against said sleeve, whereby the frictional contact between the wheels may be regulated, as set forth.

In testimony whereof I hereunto affix my signature in presence of two witnesses.

RICHARD WYLIE.

Witnesses:

JAMES A. DALY,
JOHN F. HATTEL.
